UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

STITCHED BUTTONHOLE.

Application filed November 4, 1924. Serial No. 747,723.

To all whom it may concern:

Be it known that I, EDWARD B. ALLEN, a citizen of the United States, residing at Newtown, in the county of Fairfield and State 5 of Connecticut, have invented certain new and useful Improvements in Stitched Buttonholes, of which the following is a specification, reference being had therein to the accompanying drawings.

10 This invention has for an object to provide a stitched buttonhole which is particularly adapted for knit goods and which strongly resists deformation and yet is flat and flexible, as distinguished from the rigid 15 and wiry buttonholes heretofore produced in knit goods work.

To the attainment of the ends in view, the invention comprises a knitted body-fabric in which is stitched an overseam having 20 purls along both its inner and outer edges, substantially the entire space between such purls being filled by a strong but soft yarn filler which is compressed into a flattened condition and widened out by the covering-thread loops of the overseam, so as to substantially fill the space between the purled edges. The present overseam comprises a 25 zigzag needle-thread and two looper-threads, which are formed alternately into covering-thread loops extending across the full width 30 of the overseam. Such an overseam is particularly efficacious, in combination with a soft yarn filler, in that the covering-thread loops extending alternately from one to the other side of the overseam, effectively cover 35 and conceal the soft yarn which would be inclined to stick up and show between the cross-threads of the usual buttonhole overseams. A further feature of the invention is 40 the bringing together of the ends of the above-described overseam to form a fly-bar, whereby great resistance to stretching is, with greater certainty than heretofore, imparted to the buttonhole.

45 It is found that the widening out of the soft yarn filler, under the binding pressure of the covering-threads, makes it more certain that loops of the needle-thread will be passed through such cord to anchor the latter as the sewing of the second side of the buttonhole reaches the point of overlapping the initial stitches. In other words, the wider the filler, the greater the likelihood 50 that needle-loops will be passed through the same during the sewing of the fly-bar. The

soft yarn filler also seems to be peculiarly efficacious in combination with the particular overseam referred to, in that such seam does not slide easily relatively to such filler. Just why this is so is not clearly apparent 60 but is probably due to the embedding of each looper-thread loop into the yarn by the pressure of an overlapping looper-thread loop, thus forming a plurality of effective 65 gripping points.

In the accompanying drawings, Figs. 1 and 2 are plan views, respectively, of the looper-thread and needle-thread sides of a 70 stitched buttonhole embodying the invention. Fig. 3 is a section on the line 3—3, Fig. 1; and Fig. 4 is a cross-section of the soft yarn filler, with a showing in dotted lines of how the filler is widened out under the pressure of the covering-threads.

In the embodiment of the invention illustrated 75 1 represents a knitted body-fabric which, as is well known, is easily stretched transversely of its wales 2. Such fabric has formed therein a buttonhole overseam comprising a zigzag needle-thread 3 which is 80 formed alternately into slit-stitch and depth-stitch needle-loops 4, 5, respectively, passing through to the other side of the fabric. The needle-thread loops are keyed by the alternately formed loops of a pair of looper-threads. The loop 6 of one looper-thread 85 7 enter and key the depth-stitch needle thread loop 5 and are entered and keyed by the subsequently formed slit-stitch needle-thread loop 4. The loops 8 of the other 90 looper-thread 9 enter and key the slit-stitch needle-thread loops 4 and are entered and keyed by subsequently formed depth-stitch needle-thread loops 5. The various inter-linked loops form inner and outer purls 95 10, 11, along the rows of slit- and depth-stitch loops 4 and 5, or along the inner and outer margins of the overseam.

100 Bound down and deformed into flattened condition within the overseam, on the looper-thread side of the body-fabric, is the soft yarn filler 12 which was initially circular as shown at 13, Fig. 4.

The soft yarn filler 12 is widened out 105 under the pressure of the overlapping looper-thread loops 6, 8, so as to substantially fill the space between the purls 10 and 11. The tendency is to flatten the yarn to an elliptical form, Fig. 3, so that the purls 10 and 11 stand at about the same height as 110

the threads binding the yarn filler. Thus the seam is of a characteristically flat and attractive appearance. Moreover it possesses the desired quality of flexibility and is 5 not at all wiry.

The finishing end of the overseam is sewn over the beginning end to form a fly-bar and, by reason of the widening out of the yarn filler 12 under the pressure of the covering- 10 threads, there is greater certainty that needle-thread loops will be sewn through the beginning yarn end to anchor the same against slippage.

The present buttonhole has been found 15 strongly resistant to longitudinal deformation, even when formed in knit goods without an interlining of woven material. It is probable that this very desirable property is in large measure due to the embedding 20 of each looper-thread loop into the yarn by the pressure of an overlapping looper-thread loop at the points *g*, thus forming a plurality of effective gripping points.

It is preferred to incorporate an additional 25 yarn filler 14 in the overseam at the needle-thread side of the button hole.

Having thus set forth the nature of the invention, what I claim herein is:—

1. In a stitched buttonhole, the combina-

tion with a knitted body-fabric having a 30 buttonhole-slit, of a buttonhole overseam including a zigzag needle thread formed alternately into depth-stitch and slit-stitch loops which pass through the body-fabric, and a pair of looper-threads formed alternately 35 into loops, the loops of one looper-thread entering and keying the depth-stitch needle-thread loops and being entered and keyed by the subsequently formed slit-stitch needle-thread loops, and the loops of the 40 other looper-thread entering and keying the slit-stitch needle-thread loops and being entered and keyed by the subsequently formed depth-stitch loops, the interlinked 45 loops forming inner and outer purls along the rows of depth- and slit-stitch needle-loops, and a soft yarn strand substantially filling the space between said purls and held flattened by the overlying looper-thread loops.

2. A stitched buttonhole according to 50 claim 1, with the ends of the overseam sewn in overlapping relation beyond one end of and in line with the buttonhole-slit to form a fly-bar.

In testimony whereof, I have signed my 55 name to this specification.

EDWARD B. ALLEN.
